UNITED STATES PATENT OFFICE

RICHARD SPENCER, OF FORT WORTH, TEXAS

DESIGN FOR A HOROSCOPE

Application filed June 9, 1932. Serial No. 44,022. Term of patent 3½ years.

To all whom it may concern:

Be it known that I, RICHARD SPENCER, a citizen of the United States, residing at Fort Worth, in the county of Tarrant and State of Texas, have invented a new, original, and ornamental Design for a Horoscope, of which the following is a specification, reference being had to the accompanying drawing, forming part thereof.

I claim:

The ornamental design for a horoscope as shown.

RICHARD SPENCER.
